US0D1113424S

(12) **United States Design Patent** (10) **Patent No.:** **US D1,113,424 S**
(45) **Date of Patent:** **** Feb. 17, 2026**

(54) **TUBE**

(71) Applicant: **REV Robotics LLC**, Carrollton, TX (US)

(72) Inventors: **Nicholas James Coussens**, Chicago, IL (US); **Orion Christopher DeYoe**, Irving, TX (US); **Gregory Elliott Needel**, Coppell, TX (US); **David Aaron Yanoshak**, Dallas, TX (US)

(73) Assignee: **REV Robotics LLC**, Carrollton, TX (US)

(**) Term: **15 Years**

(21) Appl. No.: **29/834,696**

(22) Filed: **Apr. 13, 2022**

(51) **LOC (15) Cl.** **08-05**

(52) **U.S. Cl.**

USPC **D8/354**

(58) **Field of Classification Search**

(57) **CLAIM**

The ornamental design for a tube, as shown and described.

DESCRIPTION

FIG. 1 is a perspective view taken from the front, the top and the right of a tube.

FIG. 2 is a perspective view taken from the rear, the bottom and the left of the tube.

FIG. 3 is a right side view of the tube.

FIG. 4 is a left side view of the tube.

FIG. 5 is a front view of the tube.

FIG. 6 is a rear view of the tube.

FIG. 7 is a top view of the tube; and,

FIG. 8 is a bottom view of the tube.

1 Claim, 6 Drawing Sheets
